UNITED STATES PATENT OFFICE

2,277,633

ELECTRIC LAMP AND MOUNTING

Joseph D. Ceder, East Cleveland, Ohio, assignor
to General Electric Company, a corporation of
New York

Application January 8, 1938, Serial No. 184,046

2 Claims. (Cl. 240—10.6)

My invention relates to electric incandescent lamps or similar devices comprising an electric energy translation element, such as a filament, sealed within a bulb or envelope. More particularly, my invention relates to electric incandescent lamps of the prefocused miniature type in which the filament or light source is mounted in predetermined relation with respect to a portion of the lamp.

In the use of miniature lamps for flashlight and similar service, wherein the lamp is mounted in a reflector member, it is desirable that the filament be accurately located at the focal point of such reflector member in order to obtain the most efficient beam of light. Accordingly, one object of my invention is the provision of means for simply and accurately centering the filament of a flashlight or similar lamp with respect to the focal point of a reflector. Another object of my invention is the provision of an electric incandescent lamp of the prefocused type, in which the filament is mounted in predetermined relation with respect to a reflector-engaging shoulder on the bulb. Still another object is to provide a lamp having a cylindrical bulb with the filament located between the said shoulder and the tip or forward end of the bulb so that the lamp may be inserted in a reflector from the rear.

Further objects and advantages of my invention will appear from the following description of a species thereof and from the accompanying drawing.

In the drawing, Fig. 1 is a longitudinal sectional view through the bulb of a lamp comprising my invention, showing the manner in which the filament is mounted in predetermined relation with respect to a portion of the bulb during the sealing-in operation; Fig. 2 is a longitudinal sectional view of a completed lamp comprising my invention; and Fig. 3 is a longitudinal view, partly in section, showing the manner in which a lamp comprising my invention may be mounted in the reflector member of a flashlight to accurately position the lamp filament at the focal point of such reflector member.

Referring to the drawing, the particular lamp illustrated is of the conventional butt-sealed miniature type used, for example, in flashlights. The lamp comprises a bulb 10 of cylindrical shape and is provided with an annular protuberance 11 adjacent its lower or base end 12, to which end is sealed an exhaust tube 13. A pair of leading-in wires 14, 15 have portions thereof sealed in the joint formed by the bulb 10 and exhaust tube 13. A filament 16 is mounted on the leading-in

wires 14, 15 which are held in spaced relation within the bulb by a bead 17 of insulating material. The filament 16 is accurately mounted within the bulb at a predetermined distance d from, and in a predetermined plane (preferably 90°) with respect to a plane A—A passing through the forward shoulder portion 18 of the annulus 11 of the bulb at right angles to the longitudinal axis of said bulb. This plane A—A represents the line of engagement between the bulb seal holder 19 (Fig. 1) and the annulus 11 during the sealing-in operation. The location of the plane A—A along the longitudinal axis of the bulb is therefore determined by the diameter of the ring-engaging edge 20 of the opening 21 in the bulb seal holder.

The base 22 comprises a cylindrical metal shell 23 provided at its outer end with a body of insulating material 24, preferably glass, having an opening 25 therein, and a metal eyelet 26 fused to the end thereof. The leading-in wire 15 is threaded through the base insulating opening 25 and electrically connected to the metal eyelet 26, such as by soldering, to thereby form the end contact 27. The other leading-in wire 14 is bent back over the inner edge or rim of the base shell 23 and soldered to the outer surface of said shell, as shown at 28 in Fig. 2. The base 22 is secured to the bulb by a quantity of cement 29.

Fig. 3 illustrates a method of mounting a lamp comprising my invention in a flashlight reflector so as to accurately position the filament at the focal point of the same. The reflector 30 is formed with a centrally located opening 31 the diameter of which is exactly the same as that of the opening 21 in the bulb seal holder at the bulb-engaging edge 20 thereof. The lamp is inserted in the reflector opening 31 from the rear of the reflector, and the annulus 11 on the bulb is pressed against the rear edge of the reflector opening 31 by means of a light spring 32 mounted on a fibre disc 33 and disposed between the lamp end contact 27 and the center contact 34 of a battery 35 and serving as the electrical connection therebetween. Since the diameter of the reflector opening 31 is exactly the same as that of the opening 21 in the bulb seal holder 19, the reflector will accordingly engage the forward shoulder portion 18 of the annulus 11 along the previously referred to plane A—A. The filament 16 of the lamp will therefore be positioned at the distance d from the rear edge of the reflector opening 31. By making this distance d exactly equal to the distance of the reflector focal point from the rear edge of the reflector opening 31,

the lamp filament 16 will be accurately located at such focal point.

The flashlight casing or housing 36 may be provided with additional lamp support means comprising a plurality of light spring fingers 37 mounted on a fibre washer 38 and adapted to engage the lamp base shell 23 and maintain the lamp in alignment with the longitudinal axis of the casing 36. At the same time, these spring fingers 37, in conjunction with the switch contact arm 39 and switch 40, constitute the electrical connection between the base shell 23 and the casing 36.

If desired, the spring member 32 between the lamp end contact 27 and the battery center contact 34, together with its supporting fibre disc 33, may be omitted and only the conventional spring 41 at the rear of the battery casing, between the end cover 42 thereof and the battery 35, used to force the annulus 11 into engagement with the rear edge of the reflector opening 31.

While the annulus 11 on the bulb is the preferred form of construction, the bulb, if desired, may be provided instead with three or more outwardly extending protuberances or projections spaced approximately equally around the circumference of the bulb. Such projections will obviously perform the same function as the aforementioned annulus 11.

What I claim as new and desire to secure by Letters Patent of the United States is:

1. The combination of a concave reflector having a centrally located opening therein, an electric lamp comprising a tubular bulb extending

5 into said reflector from the rear thereof, said bulb having an integral outwardly extending annulus thereon forming a shoulder facing forwardly of the bulb and engaging the rear of said reflector around the said opening therein and a concentrated light source located in the portion of said bulb within said reflector at a definite predetermined distance from the plane of the forward face of said shoulder, and means behind said reflector for engaging said lamp and pressing the said forward face of said shoulder thereon in engagement with the rear of said reflector to hold the said light source in definite relation to the focus of said reflector.

2. In a flashlight, the combination of a casing, a concave reflector within said casing having a centrally located opening therein, an electric lamp comprising a tubular bulb extending into said reflector from the rear thereof, said bulb having an integral outwardly extending annulus thereon forming a shoulder facing forwardly of the bulb and engaging the rear of said reflector around the said opening therein and a concentrated light source located in the portion of said bulb within said reflector at a definite predetermined distance from the plane of the forward face of said shoulder, and means within said casing behind said reflector for engaging said lamp and pressing the said forward face of said shoulder thereon in engagement with the rear of said reflector to hold the said light source in definite relation to the focus of said reflector.

JOSEPH D. CEADER.
